CLAIM

We claim the ornamental design for a front cover for four wheel vehicle, as shown and described.

DESCRIPTION

FIG. 1 is a perspective view from the front side of a front cover for four wheel vehicle.

FIG. 2 is a perspective view from the front side thereof.

FIG. 3 is a perspective view from the rear side thereof.

FIG. 4 is a perspective view from the rear side thereof.

FIG. 5 is a front elevation view thereof.

FIG. 6 is a rear elevation view thereof.

FIG. 7 is a right side elevation view thereof.

FIG. 8 is a left side elevation view thereof.

FIG. 9 is a top plan view thereof.

FIG. 10 is a bottom plan view thereof; and,

FIG. 11 is a perspective view thereof and reduced scale and shown in condition of use.

The broken lines shown in the drawings are for illustrative purposes only and form no part of the claimed design.
